(57) **CLAIM**

The ornamental design for a holder for a beverage container, as shown and described.

DESCRIPTION

FIG. 1 is a perspective view of a holder for a beverage container according to the present invention;

FIG. 2 is a front elevation view of the holder for the beverage container illustrated in FIG. 1;

FIG. 3 is a rear elevation view of the holder for the beverage container illustrated in FIG. 1;

FIG. 4 is a left side elevation view of the holder for the beverage container illustrated in FIG. 1;

FIG. 5 is right side elevation view of the holder for the beverage container illustrated in FIG. 1;

FIG. 6 is a top plan view of the holder for the beverage container illustrated in FIG. 1;

FIG. 7 is a bottom plan view of the holder for the beverage container illustrated in FIG. 1;

FIG. 8 is a perspective view of the holder for the beverage container holding device illustrated in FIG. 1 being affixed to a door of a refrigerator and holding a beverage container. The broken line showing of a refrigerator, a beverage container held within a sleeve is included for the purpose of illustrating environmental structure that forms no part of the claimed design; and,

FIG. 9 is a perspective view of the holder for the beverage container illustrated in FIG. 1. The broken line showing of a refrigerator, a beverage container held within a sleeve is included for the purpose of illustrating environmental structure that forms no part of the claimed design.
